TURNTABLE FOR TALKING MACHINES.

1,409,432.

Specification of Letters Patent. Patented Mar. 14, 1922.

Application filed March 13, 1918. Serial No. 222,199.

To all whom it may concern:

Be it known that I, ANTHONY VASSELLI, a citizen of the United States, and a resident of the city of Newark, county of Essex, 5 and State of New Jersey, have invented a certain new and useful Turntable for Talking Machines, of which the following is a specification.

My invention relates to means for securing a pad to turn-tables of disc talking machines and the production of means so that such pad will not become disarranged in use and to prevent the unraveling of the fabric constituting the pad.

15 In disc talking machines, it is the common practice to secure a felt disc to the top surface of the turn-table to form a soft, yielding pad or cushion means on which the record disc rests. The frictional engagement 20 of the record disc with the felt pad is depended on to prevent relative rotation of the record disc and turn-table when the former is engaged by the stylus of the reproducer.

25 The felt disc or pad has been found unsatisfactory for several reasons, the principal reason being that when the pad has been used for some time, its upper surface becomes smooth, shiny and slippery, and the 30 engagement of the record groove in the moving disc with the stationary reproducer stylus will cause the record disc to slip and permit the turn-table to rotate at a higher speed than that of the record disc.

35 The employment of a pad composed of velvet or other pile fabric has been proposed, but the material was found objectionable for the reason that a disc cut of textile fabric will present very short threads 40 at four points on its periphery; the warp threads being shortest where the woof is longest, and the warp being longest where the woof is shortest. The fabric will unravel at these four points, and the short

45 threads will become disengaged from the pad. Such threads are likely to get on the surface of the record disc and into the record groove, and mar the reproduction. The ends of the long threads which remain, will 50 project beyond the body of the pad, will curl or kink, and form knots or bunches which lying under the record disc and between it and the turn-table, will prevent the

disc from lying flat on the same. The edge of the pad will be ragged, fringed and untidy in appearance. The back of a pile fabric such as plush or velvet being of hard twisted yarn will be smooth and permit the pad to slip relatively to the turn-table.

55 A pile fabric makes an ideal and more effective covering for a turn-table than a felt pad as the ends of the cut pile threads form an effective friction surface. The pile must be worn entirely off before the top surface becomes hard and shiny and thereby allow 60 the record disc to slip.

65 The objects of my invention are to prevent the unraveling of the edges of a disc of textile fabric, such as velvet, plush or the like, to provide means for securing a 70 pad to a turn-table to prevent relative movement of the pad and turn-table, to provide means for protecting the covering or pad of a turn-table, to provide a pad which will not become disarranged, and improve the 75 appearance of a turn-table provided with fabric covering.

The invention contemplates the provision of means for supporting and retaining the pad in its proper position on the turn-table 80 to protect the fabric from injury, and to effectively prevent unraveling of the fabric.

85 A further object of the invention is the provision of means of the character described, which are extremely simple in construction, neat and attractive in appearance, thoroughly reliable and efficient in its purpose, and inexpensive to manufacture.

90 With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

95 The inventive idea involved is capable of receiving a variety of mechanical expressions, some of which for the purpose of illustrating the invention, are shown in the accompanying drawings.

100 The invention will be first described in connection with the accompanying drawings, wherein similar reference characters 105 are used to designate corresponding parts

throughout the several views, and then more specifically defined and indicated in the appended claims.

In the drawings,—

5 Fig. 1 is a top plan view of a talking machine turn-table provided with my invention;

Fig. 2 is a sectional view on an enlarged scale, said section being taken on the line 10 2—2 of Fig. 1;

Fig. 3 is a detail view of a modification; and

Figs. 4 and 5 are detail sectional views of additional modifications.

15 In the drawings, 1 designates a talking machine turn-table of any approved type. The turn-table has a central boss or hub having an orifice 2 for the passage or reception of the upper end of the turn-table 20 spindle. The periphery of the turn-table is thickened on its lower face to form a downwardly extending flange 3. The upper surface of the turn-table is removed to form an annular recess 4 adjacent to the

25 periphery thereof for the purpose herein-after described. A circular disc pad 5 of velvet, plush or other pile fabric is placed in position on the upper surface of the turn-table. The pad 4 is of such a diameter as to 30 permit of the proper adjustment of the securing and retaining means as hereinafter described.

A metal ring 6 having a cylindrical flange 7 is placed in position over the edge of the 35 turn-table 1, the ring 6 depressing the outer edge of the disc pad 5 into the recess 4. The flange 7 is secured to the periphery of the turn-table by soldering or in any suitable manner so as to retain the ring in position. The depth of the recess 4 is such that 40 the ring 6 will lie below the level of the top of the disc pad 5, and thereby in no manner interfere with the proper holding of the disc record by the pad.

45 The center of the pad 5 is provided with a perforation 8 for the passage of the tip of the turn-table spindle, and in order to prevent unraveling of the textile fabric at this edge of the said perforation, there is 50 provided a metal or other binding in the form of an eyelet 9 having an opening corresponding and registering with the orifice 2 of the turn-table shaft and the perforation 8 of the pad 5. Such eyelet has an annular 55 groove on its periphery into which groove the pad is inserted to prevent unraveling.

In the modification shown in Fig. 3, a flange 11 is formed as an integral part of and over the upper surface of the turn-table 60 surrounding the orifice 2, and this flange is turned down over the edge of the opening 8 in the center of the pad, thereby forming an annular recess or groove between the flange and the surface of the turn-table into 65 which is set the edge of the fabric surround-

ing the opening 8 in the pad 5 to prevent unraveling of its edge.

The modification shown in Fig. 4 illustrates a construction in which the outer edge of the recess 4 is formed by an upstanding bead or projection 1^a on the periphery of the turn-table. The retaining ring 16 engages the top of the bead or projection and the edge of the pad 5 while the flange of the ring may be soldered in place as in Fig. 70 2 or it may be forced in place and held by friction.

Fig. 5 shows a modification in which the turn-table of Fig. 4 is employed and the flange of the ring 17 is turned under the 80 flange 3 of the turn-table 1 as at 18.

In both these forms, it will be observed that the ring 16 engages the bead or projection 1^a and prevents the ring from being pressed too hard or forcibly upon the edge 85 of the pad, the bead being of such width and height to permit the ring to overhang and engage the edge of the pad to hold it in place and protect it against raveling.

By my invention the disc pad is secured 90 in place on the top of the turn-table, the outer and inner edges are bound to prevent unraveling, the binding and securing elements may be highly polished and plated or colored, as desired, so as to greatly improve the appearance of the apparatus.

When the pad as above applied to the turntable becomes worn out and does not effectively serve its purpose of frictionally engaging the record, it may readily be removed by simply working or pulling its outer peripheral edge from beneath the overhanging flange of the retaining ring 16 or 100 17 and the pad lifted from the turntable with its attached reinforcing eyelet, as in Fig. 2, or in the case of the reinforce for the spindle opening made integral with the turn-table, as in Fig. 3, the edge of the pad at the spindle opening may be drawn or 105 pulled from the groove formed by the flange 11, and the pad lifted from the table, and when thus removed, the turntable may be supplied with a new pad, and in case the pad is of the form shown in Fig. 2, with the attached reinforcing eyelet at the spindle 110 opening, it is simply necessary to slip the reinforced spindle opening over the spindle of the talking machine and then the outer or peripheral raw edge of the pad may 115 readily be worked or slipped under the overhanging flange of the ring 17, the bead or projection 1^a of the turntable, upon which the flange of the ring 17 rests, affording sufficient space between the groove 4 and 120 said flange to receive the edge of the pad. In the construction shown in Fig. 3, where the spindle opening of the pad is not provided with an attached reinforcing eyelet, the raw edge of the pad at the spindle opening 125 may readily be forced into the groove 130

- formed by the overhanging flange 11 at the spindle opening in the turntable, and said raw edge effectively prevented from becoming unraveled.
- 5 From the foregoing it is obvious that a new pad may be readily inserted and the old one removed by using fastening means which hold the ring by spring pressure in frictional engagement with the periphery of the turn-table in place of using solder to retain said ring in position.
- The rings may be constructed of any desired material, metal, rubber, wood, textile material or the like.
- 10 I desire to have it understood that my invention may be carried out by the use of pads made of materials other than pile fabrics such as velvet or plush. The ordinary felt or any other suitable material may be employed.
- 15 The operation will be obvious from the above description and accompanying drawings.
- In accordance with the provisions of the patent statute, I have described the principle of my invention together with the apparatus which I now consider to represent the best embodiment thereof, but I desire it understood that my invention is not confined to the particular form of apparatus herein shown and described, the same being merely illustrative, and that the invention can be carried out in other ways without departing from the spirit of my invention,
- 20 and, therefore, I claim broadly the right to employ all equivalent instrumentalities coming within the scope of the appended claims, and by means of which objects of my in-
- vention are attained, and the new results accomplished, as herein set forth, as it is obvious that the particular embodiments herein shown and described are only some of many that can be employed to attain these objects and accomplish these results.
- Having now described my invention, what I claim and desire to secure by Letters Patent is as follows:
1. A turntable for talking machines, having a bead or projection rising from the periphery thereof, and an annular recess in the top of the turntable adjacent to said bead or projection, an annular flange overhanging said recess, and a pad fitted upon said turntable with its peripheral edge extending into said recess, said flange engaging the edge of the pad to hold and protect the same in said recess.
2. A turntable for talking machines, having a bead or projection rising from the periphery thereof, and an annular recess in the top of the turntable adjacent to said bead or projection, a pad fitted upon said turntable with its peripheral edge extending into said recess, and a ring fitted to the periphery of the turntable and having a flange resting upon said bead or projection and overhanging said recess and engaging the edge of the pad to hold and protect the same in said recess.

This specification signed and witnessed this 12th day of March, 1918.

ANTHONY VASSELLI.
